DUCK HUNTER'S CRUTCH

Benjamin F. Moore, P.O. Box 2071, Memphis, Tenn.
Filed Nov. 13, 1959, Ser. No. 852,674
4 Claims. (Cl. 211—64)

The present invention relates to certain new and useful improvements in novel multipurpose extensible and contractile staff expressly, but not necessarily, designed and adapted for use by hunter's particularly in that it lends itself for use as a walking stick, a staff, a so-called emergency crutch, and, what is most important, as a gun holder.

As will be hereinafter more clearly evident the device is unique as a walking stick for the reason that it is longitudinally extensible and retractible and therefore may be adjusted to be used by a hunter for support when walking through flooded areas and trudging over rough and uncertain terrain.

In addition and as briefly touched upon the device is a staff susceptible of being satisfactorily used by the hunter to maintain his balance while wading through swamps, wet matted twigs and similarly covered areas, for feeling his way along in water for submerged logs, brush or deep holes that would normally cause the hunter to stumble or perhaps step in an unexpected depression above his boots.

In the sense that the invention is a "crutch" it has the necessary mechanical expedients and arrangement thereof capable of being reliably used just in case the hunter might turn and sprain an ankle or twist a knee or limb out of place.

As is perhaps already evident from what has been stated above the essence of the invention may be said to reside in the use of the device as a stake or rack and gun holder. The construction is such that the invention may be used by the hunter to relieve himself of the necessity of holding his gun in his hands during the time when the prey (doves, duck, etc.) are not on the move, that is, not flying. To this end the cooperating components may be properly adjusted to hold the gun in proper position so as to require a minimum of effort to pick it up and make a quick shot.

Briefly summarized, the invention comprises an elongated barrel or cylinder and a cooperating rod or leg which is telescopically mounted therein. The two parts are adjustably joined by way of a suitable chuck. A specially designed head on the upper end of the barrel or cylinder has several purposes to be revealed. A bracket is mounted on the median portion of the barrel and this also serves a number of purposes to be described.

Other objects, features and advantages will become more readily apparent from the following description and the accompanying illustrative drawing. In the drawing, wherein like numerals are employed to designate like parts throughout the views:

FIG. 1 is a view in perspective of a multipurpose hunter's utility staff or crutch constructed in accordance with the principles of the invention.

FIG. 2 is a similar view with the gun omitted and with the leg contracted into the cylinder or barrel.

FIGS. 3 and 4 are enlarged detail sections on the lines 3—3 and 4—4, respectively of FIG. 1.

In the drawing the elongated barrel or cylinder is denoted by the numeral 6 and this is of suitable cross-section and length. In experimental models this part has been of aluminum tubing and may be some three feet, more or less in length. A length of aluminum tubing is also employed to provide the extensible and retractible rod or leg 8. Here again this part may be about three and one-half feet in length. In any event the lower end

2

thereof is suitably pointed as at 10 so that it may be forced into the ground or bed of the stream or other body of water in an obvious manner. The upper end portion 12 as shown in FIG. 3 is telescopically fitted in the bore 14 of the barrel 6 and the lower end of the barrel is provided with screw-threaded longitudinally slit fingers 16 defining grips and serving to accommodate the threaded portion of the attachable and detachable clamping and assembling nut 18. These components together provide a satisfactory chuck which permits the leg to be extended or retracted or adjusted and held in any intermediate stage or position.

There is a novel head 20 mounted on the upper end and this head is in the nature of a short piece or bar of aluminum having a socket therein and defining what may be described as a cap 22 which is capped over the end of portion 24 with the body or arm portion 26 projecting at right angles and gradually tapered and then formed into a return bend 28 providing a hook-like seat for the barrel 30 of the shot gun 32. The butt 34 of the gun is adapted to rest atop the edge of a foot 36 having a toe 38 at the outer end thereof. The foot is interposed between the spaced parallel terminal end portions 40 of a split clamping band or ring 42. This band embraces the barrel and the parts are assembled and held together by a bolt 44 and wing nut 46. The clamp may be also described as a bracket and is rotatable and slideable and may be moved toward and from the head. The cap portion of the head is removably held in place by setscrew 48. It follows that the hooked head member 26 may be located above the foot and the foot may be extended to assume a horizontal gun butt supporting position.

It will be evident that by loosening he knurled lock or sleeve nut 18, pulling out the telescoping tube or leg section 8 the desired length of the over-all device may be attained and then by tightening the chuck, the two parts provide what may be described as a staff to be used while wading through water. For the crutch all that is necessary is to adjust the height to fit under the arm in the same manner as the staff. In this instance the hooked head member 26 provides an armpit saddle resembling the saddle on an ordinary crutch and the bracket attached foot 36 may be used as a hand piece or grip. Upon arriving at the duck blind or stand or other position for hunting the user lengthens the staff to the desired length. In practice the staff could be made some six and one-half feet or seven feet in length. It may be telescoped into half this length if desired. The chuck and accompanying sleeve 18 makes possible the desired length adjustment. The pointed end 10 permits the device to be staked into the ground. FIG. 1 shows how the toe-equipped foot 36 provides a support for the butt of the gun and how the barrel of the gun is seated and held in the hook 28.

By placing the gun butt on the rest or foot and the barrel in the hook the device is "all set" and provides a highly satisfactory gun holder which will enable the hunter to have full use of his hands and arms and will at the same time relieve him of the necessity of holding or carrying a gun weighing some six to ten pounds over long periods of time. With the gun racked on the holder it is in a ready-to-use quick-action position.

The foregoing is considered as illustrative only of the principles of the invention. Further, since numerous modifications and changes will readily occur to those skilled in the art, it is not desired to limit the invention to the exact construction and operation shown and described, and accordingly all suitable modifications and equivalents may be resorted to, falling within the scope of the invention as claimed.

What is claimed as new is as follows:

1. A device for use by a hunter comprising an elongated stake having a pointed lower end adapted to be embedded in the ground with the stake extending vertically or approximately so, a vertically elongated support barrel fitted slidably on said stake, means connecting the barrel and stake together so that the same may be telescopically collapsed into small compass when the device is not in use, means on the respective end portions of the barrel for supporting a gun in a ready-to-pick-up and use position, said means embodying a one-piece rigid head capped over and mounted on the upper end of the barrel, said head having a horizontal member disposed at right angles to said barrel and projecting beyond and terminating in a rigid hook, the bill of said hook being directed toward said barrel and providing a seat spaced from but facing the barrel and adapted for removable reception of the gun's barrel, said means also including a separate bracket mounted on the lower end portion of said support barrel and provided with a hinged folding foot adapted to removably seat and support an end portion of the gun butt, said foot being generally parallel to and located beneath said right angular disposed hook-equipped member.

2. The structure defined in claim 1 and wherein the crotch of said seat is vertical and is approximately in line with a plane parallel to the vertical axis of said barrel, the distance of the crotch from the axis of the barrel being predetermined so that when the barrel of the gun is seated and propped in its supported position there is nothing to hinder quick removal thereof from said seat.

3. The structure defined in claim 2 and wherein said foot terminates at a free outer end in an upstanding toe which may be positioned properly in relation to the aforementioned seat so as not to interfere with the handling of the butt and stock of the gun, the upper lengthwise edge of said foot and toe conjointly providing a rest for the butt of the gun, and said bracket being slidably and rotatably mounted on the support barrel so that the position of the foot may be properly related to the aforementioned hook and seat so that no hindrance to the gun pickup and handling step is present.

4. For use by a duck hunter, a gun holder and trudging staff combined comprising a vertically elongated rigid stake having a pointed lower end adapted to be embedded in the ground so that the stake may extend vertically

or approximately so above ground level, a correspondingly elongated sleeve constituting a barrel and fitted slidably over the stake, said stake being adapted to telescope into the bore of the barrel when not being used, means at the lower end of said barrel for clampingly engaging the stake in a manner to allow the stake to be either held in the barrel in a concealed retracted manner or projected a desired distance beyond the lower end of the barrel and clamped to said barrel, a rigid cap removably capped over the upper end of the barrel and provided with a setscrew engaging the barrel and allowing the cap to be rotated and clamped in any desired position or completely removed, said cap having an arm radiating from one marginal side and disposed in a horizontal plane, said arm projecting at right angles relative to the vertical axis of the barrel and being gradually tapered toward the outer free end of the arm and formed into a return bend directed toward the barrel and providing a hook-like seat for removable reception of a portion of a barrel of a shotgun, a split clamping band slidably and clampingly mounted on the first-named barrel between the upper and lower ends of the latter barrel, said clamping band constituting a bracket constituting a rest for the butt of the gun's stock, said rest comprising a foot having an inner end adjustably connected to the split end portions of the clamping band, said foot having an outer end provided with an upstanding butt retaining toe, said foot being foldable against the first-named barrel to an out-of-the-way position when not in use and projected outwardly to a position radiating from the barrel when in use, the clamping band permitting the position of the foot to be properly located in relation to the gun barrel seating hook whereby the gun may be reliably and accessibly supported in a ready-to-pick-up and shoot position.
